(57) **CLAIM**

The ornamental design for an alternator bracket, as shown
and described.

DESCRIPTION

FIG. 1 is a first perspective view of a first design of an
alternator bracket;

FIG. 2 is a second perspective of the design of FIG. 1;

FIG. 3 is a top view of the design of FIG. 1;

FIG. 4 is a bottom view of the design of FIG. 1;

FIG. 5 is a left side view of the design of FIG. 1;

FIG. 6 is a right side of the design of FIG. 1;

FIG. 7 is a front view of the design of FIG. 1;

FIG. 8 is a rear view of the design of FIG. 1;

FIG. 9 is a first perspective view of a second design of an
alternator bracket;

FIG. 10 is a second perspective of the design of FIG. 9;

FIG. 11 is a top view of the design of FIG. 9;

FIG. 12 is a bottom view of the design of FIG. 9;

FIG. 13 is a left side view of the design of FIG. 9;

FIG. 14 is a right side of the design of FIG. 9;

FIG. 15 is a front view of the design of FIG. 9; and,

FIG. 16 is a rear view of the design of FIG. 9.

The broken lines shown in the drawings are for the purpose
of illustrating portions of the article and form no part of the
claimed design.

1 Claim, 16 Drawing Sheets
